UNITED STATES PATENT OFFICE.

CORTEZ GATEWOOD, OF WASHINGTON, DISTRICT OF COLUMBIA, ASSIGNOR TO HIMSELF, AND ROBERT H. DAVIS, ALEXANDER T. HARMS, AND THOMAS B. HARMS, OF NEW YORK, N. Y.

DESIGN FOR A PUZZLE-BLOCK.

SPECIFICATION forming part of Design No. 28,775, dated May 31, 1898.

Application filed April 11, 1898. Serial No. 677,240. Term of patent 3½ years.

To all whom it may concern:

Be it known that I, CORTEZ GATEWOOD, a citizen of the United States, residing at Washington, District of Columbia, have invented and produced a new and original Design for a Puzzle-Block, of which the following is a specification, reference being had to the accompanying drawings, forming a part thereof.

Figure 1 is a plan view of a puzzle-block, showing my design; and Fig. 2 is a section on the line 2 2 of Fig. 1.

The leading feature of my design consists in a game-board comprising a rectangular

board upon which is a star having a broad tinted outline, with depressions 3 at the extreme points of the star and depressions 4 at the junction of the points, the several depressions being wholly outside the star-lines. 15

I claim—

The design for a puzzle-block, herein shown 20 and described.

CORTEZ GATEWOOD.
